DESIGN FOR A COMBINED DISH AND TRAY

Jacob Heller and Michael Heller, Brooklyn, N. Y.

Application March 6, 1935, Serial No. 55,751

Term of patent 7 years

To all whom it may concern:

Be it known that we, Jacob Heller, a citizen of the United States and resident of Brooklyn, New York city, in the county of Kings and State of New York, and Michael Heller, a citizen of the United States and resident of Brooklyn, New York city, in the county of Kings and State of New York, have invented a new, original, and ornamental Design for a Combined Dish and Tray, of which the following is a specification, reference being had to the accompanying drawing, forming a part thereof.

Figure 1 is a top perspective view of a combined dish and tray showing our new design, and

Figure 2 is a front elevational view of the combined dish and tray shown in Figure 1.

The present design comprises as the principal

and dominating features thereof a relatively wide, flat flange which is highly polished and whose outer periphery is provided with a relatively wide, flat bead, and which flange has a slight downward inclination from the peripheral bead to the central depression of the dish, the walls of the central depression being substantially vertical, and the inner periphery of the flange terminating at substantially the walls of the sectional dishes and well below the upper edges of the dishes.

We claim:

The ornamental design for a combined dish and tray substantially as shown and described.

JACOB HELLER.
MICHAEL HELLER.
